UNITED STATES PATENT OFFICE.

ALFRED DON, OF 21 COOPER STREET, REDFERN, SYDNEY, NEW SOUTH WALES, AUSTRALIA.

SMOKE-CONSUMING APPARATUS FOR STEAM-BOILERS.

SPECIFICATION forming part of Letters Patent No. 376,948, dated January 24, 1888.

Application filed May 24, 1887. Serial No. 239,202. (No model.)

To all whom it may concern:

Be it known that I, ALFRED DON, engineer, a subject of the Queen of Great Britain, and residing at Redfern, Sydney, in the Colony of New South Wales, Australia, have invented a new and useful Improvement in Smoke-Consuming Apparatus for Steam-Boilers and Method of Applying the Same, of which the following is a full, clear, and exact description.

My invention relates to steam-boiler and other furnaces; and its objects are to provide the same with a simple, efficient, and inexpensive apparatus, whereby a jet of combined air and steam may be projected into the fire-box after the introduction of fuel therein, to produce an increase in the combustion of said fuel and to consume and disperse the smoke in said fire-box, which apparatus may be applied to any furnace and be adapted to receive steam from the furnace itself or from any more or less adjacent source.

The invention consists in a novel construction and arrangement of parts of the smoke-consuming apparatus, and in a novel method of applying the same to the furnace, all as hereinafter particularly described, and then pointed out in the claims.

Numerous devices have heretofore been resorted to having for their object the consumption and dispersion of smoke in the furnaces specified and the increase of combustion of fuel therein; but they have either been for the most part costly and complicated in themselves or have required for their application and operation a special construction or an alteration of the furnace, and those even of an economical character have only been partially effective in the desired direction. The introduction into such furnaces of steam, air in a cold or heated state, and jets of steam, or of steam and air combined, are all well known as aids in diminishing or preventing smoke and increasing combustion; but the apparatus heretofore employed for that purpose and the methods of applying the same have either not insured complete success, or, if successfully used, such methods and apparatus have not possessed the simplicity, efficiency, and cheapness, nor the facility of application and operation in connection with any of the furnaces

specified, which inhere to my method and apparatus.

My invention is illustrated in the accompanying drawings, forming a part of this specification, in which similar letters of reference indicate corresponding parts in the several views.

Figure 1 is a vertical sectional side elevation of part of a boiler-furnace, showing my invention applied, taken on the line *x-x* of Fig. 2. Fig. 2 is an end elevation of the same. Fig. 3 is a side elevation of my improved apparatus, a part being broken away and indicated in dotted lines. Fig. 4 is a vertical sectional view of the same, taken on the line *y-y* in Fig. 3; and Fig. 5 is a plan view of the air-pipe of the apparatus.

In said drawings, A is the fire-box; A', the steam-space; B, the furnace-door; C, an air-pipe secured to the furnace and entering the fire-box; D, a steam-pipe extending from the steam-chest to and within the air-pipe, and E a cock or valve which controls the supply of steam.

In carrying out my invention I construct the air-pipe C either of cast or wrought iron and of an oval shape in cross-section. Said pipe may have any other suitable contour, the form specified, however, being in my view the preferable one. For application to the furnace of an ordinary locomotive-boiler of the dimensions of four feet five inches by three feet eight inches, I construct said pipe of a length of eighteen inches (although that precise length is not very material) and of a diameter of four inches by two and one-half inches. Although said diameter may be slightly exceeded or diminished with approximately the same result in operation, I have found in practice that a larger or smaller pipe is not as effective as one of the diameter specified.

It will be understood that when my improved apparatus is to be employed upon larger furnaces—such, for instance, as those of marine boilers—said pipe will be constructed of a length and diameter proportioned to the size and fuel capacity of the furnace.

The pipe C is formed with a bell-shaped mouth, *a*, at its top or upper end, and its lower part is bent or curved at or nearly a right

angle with its stem, as at *b*, to adapt it to enter the fire-box, as hereinafter explained, said pipe being substantially L-shaped. Its lower extremity is formed with a bell-shaped exit, *c*, having a slight downward deflection, and at suitable distances along its stem said pipe is provided with lugs or eyes *d*, to receive bolts or screws for securing it to the furnace. The bent or curved portion of said pipe is given such an angle that a line drawn from the upper inner side of the stem of the pipe will meet the outer end of the fire-box just above the fuel therein. The faces of the bell-shaped exit *c* are formed at such an angle that lines produced therefrom will reach all the sides or angles of the fire-box opposite thereto just above the level of the fuel therein, so that jets of steam and induced currents of air passing through the pipe *C* will, by means of the deflection of said bell-shaped exit *c*, be projected equally all over the surface of the fuel, and will consume and disperse all the smoke arising therefrom. To secure this result in a furnace of the size above mentioned, I form the bell-shaped exit *c* with an angle of deflection of about three-fourths of an inch and of the dimensions of about six inches by three inches, the curve or bend of the pipe allowing said exit to extend about one and three-quarter inch within the fire-box. These dimensions and the deflection of said exit, as well as the bend of said pipe, may be varied to accommodate the apparatus to larger furnaces, as will readily be understood.

35 A steam-pipe, *D*, preferably of copper and about one-half an inch in diameter, is bent at its lower end correspondingly with the curved portion of the pipe *C*, is passed into said pipe so that its exit is just beyond the commencement of the bend of the latter pipe, and is fixed within the center of the said pipe by suitable stays or brackets, *e*. Said pipe *D* is extended upward along and over the end of the furnace as far as possible, in order to insure dryness of the steam it is to convey to a connection with the steam-chest, and is controlled at or near such connection by a suitable steam cock or valve, *E*. A steam-trap of any approved form may be placed at any desired point in the pipe *D* between the steam-cock and the mouth of the pipe *C*, to aid in securing dry steam, if preferred.

50 A valve or lid, *f*, as shown in Fig. 5, or of any other suitable and preferred construction, is provided the mouth of the air-pipe *C*, so that air may be admitted or excluded from the pipe, as required.

When my improved apparatus is to be applied to the furnace of a locomotive-boiler, I cut or form centrally of the upper edge of the door *B* an opening suited to admit the passage of the lower curved portion of the pipe *C*, so that when the door is closed an approximately tight joint is formed between it and said pipe.

65 When the apparatus is to be applied to the furnace of a marine boiler, I provide the opening for the pipe *C* at the end of the furnace in

the dead-plate immediately above the center of the upper edge of the door.

The pipe *C* is placed with its stem against the end of the furnace, so that its curved portion *b* projects within the fire-box, as shown in Fig. 1, and is secured in place by bolts or screws passed through the lugs *d* into suitable apertures in the shell of the furnace; or the lugs may be dispensed with and any other proper means be adopted to hold the pipe in place. The pipe *D* is inserted in the pipe *C*, so that its lower end enters the curved portion *b* of said pipe, and is held to place centrally of said pipe by the stays *e*, or other suitable means, as preferred, and is connected to the steam-chest and supplied with a valve in the usual manner. When fuel has been introduced into the fire-box and the door has been closed, by opening the lid of the air-pipe and opening the valve of the steam-pipe a jet of steam in the pipe *D* and a current of air induced thereby in the pipe *C* combine in the part *b* of said air-pipe and pass together out of the exit *c* into the fire-box, and will have the effect, by careful stoking on the part of the attendant, of almost immediately dispersing the smoke generated by the fuel, and, forcing it into the mass of said fuel, cause it to be consumed and at the same time render the fuel incandescent. Combustion having been thus aided, the steam may be shut off, the lid of the air-pipe being left open for about a half minute or so, to allow the air to escape.

100 I have found in practice that the use of the steam-jet for but a few seconds of time will in ordinary cases suffice; but in cases where the fuel added is bulky of itself, or is introduced in great quantity, a longer time may be required.

When it is desired to consume or disperse smoke in the fire-box before the fire is started fairly enough to make steam, or it is desired to hasten the making of steam, my apparatus 110 may be supplied with steam from another source by connecting the steam-pipe or air-pipe in any suitable manner with the same, and the operation may be conducted as effectively as when the steam is derived from the 115 furnace to which the apparatus is applied.

120 My invention is readily applied to locomotive-boilers at a nominal cost and without requiring alteration in their construction, and when applied renders the use of baffle-plates unnecessary and produces a much better result.

125 By the construction and arrangement of the air-pipe and steam-pipe, as herein shown and described, I am enabled to secure a direct and instantaneous effect of the steam and air upon the fuel, as both quickly combine, and the combined jet is evenly projected all around the fire-box and upon every part of the surface of the fuel.

130 The air which is induced to the pipe *C* by the vacuum created by the jet of steam is also of the temperature best suited for the desired object, being not too hot to diminish the sup-

ply of oxygen and yet sufficiently warm to obviate the disadvantages incident to the introduction of cold air into the furnace. The bell-shaped mouth of the air-pipe also aids in the induction of air by the action of the steam, and so expedites the action of the jet in the fire-box, while the bell-shaped exit insures complete action of the jet upon the fuel.

Having thus described my invention, what I claim as new, and desire to secure by Letters Patent, is—

1. As a new article of manufacture, an attachment for steam-boiler and other furnaces, consisting of an L-shaped air-induction pipe secured to the end of the furnace, and its curved portion projecting within the fire-box through an opening in the furnace, having a bell-shaped mouth fitted with a lid or valve, and a bell-shaped exit deflected downwardly above the fuel in the fire-box, said pipe being adapted

to receive a steam-supply pipe, substantially as described and shown, for the purposes set forth.

2. In an apparatus for consuming smoke in steam-boiler and other furnaces, the combination, with the L-shaped air-pipe C, having the bell-shaped mouth *a* fitted with the lid *f*, and the bell-shaped exit *c*, having a downward deflection, of a steam-pipe, D, connected to the steam-chest or other source of steam-supply, and adapted to discharge steam within the bent portion of said air-pipe, substantially as shown and described.
